UNITED STATES PATENT OFFICE.

MORGAN O. DOOLITTLE, OF JAMESTOWN, NEW YORK.

DESIGN FOR A CLOCK CASE.

Application filed May 25, 1928. Serial No. 26,854. Term of patent $3\frac{1}{2}$ years.

To all whom it may concern:

Be it known that I, MORGAN O. DOOLITTLE, a citizen of the United States, residing at Jamestown, in the county of Chautauqua and State of New York, have invented a new, original, and ornamental Design for a Clock Case, of which the following is a specification, reference being had to the accompanying drawing, forming part thereof.

In the drawing:

Fig. 1 is a front elevation of my newly designed clock case; and

Fig. 2 is a side elevation of the clock case as shown in Fig. 1.

I claim:

The ornamental design for a clock case substantially as shown.

MORGAN O. DOOLITTLE.
